UNITED STATES PATENT OFFICE.

SILAS W. ALBERTSON, OF ROSLYN, NEW YORK.

AUTOMATIC WAGON-BRAKE.

SPECIFICATION forming part of Letters Patent No. 373,548, dated November 22, 1887.

Application filed March 4, 1887. Serial No. 229,683. (No model.)

To all whom it may concern:

Be it known that I, SILAS W. ALBERTSON, of Roslyn, in the county of Queens and State of New York, farmer, have invented a certain 5 new and useful Improvement relating to Automatic Brakes for Farm-Wagons and Analogous Vehicles, of which the following is a specification.

I carry a brake-bar on the thills, and provide 10 a movable connection between the same and the running-gear, so conditioned that the connection will tighten and become firm and stiff when the animal or animals pull forward in the ordinary use of the wagon, but will move without appreciable resistance from friction 15 when it has been forced backward to or near its extreme rear position. There is a free vertical movement of the front end of the tongue or thills when pressed backward. My 20 means of preventing the action of the brake when it is desired to back the wagon are efficient and reliable.

The invention is especially adapted by its simplicity for use in farm-vehicles.

The accompanying drawings form a part of 25 this specification, and represent what I consider the best means of carrying out the invention.

Figure 1 is a side elevation of the front portion of a farm-wagon having my invention. 30 One wheel is removed. Fig. 2 is a plan view. The wagon-body is indicated by dotted lines. Fig. 3 is a vertical central section.

Similar letters of reference indicate corresponding parts in all the figures where they occur.

A is the body of the wagon; B, the bolster fixed immovably thereto, and D the front axle turning on a king-pin. (Not shown.)

E E are the front hounds. So far as yet described all these parts, as also the curved iron braces F F, which as the front axle swivels on the king-pin move backward and forward between the bolster B and the wagon-body A, 45 are of ordinary and long-approved construction. A stout cylindrical bolt, G, connects the hounds in the position represented.

M is a brake-bar extending across in front of the forward wheels, H H. It carries brake-blocks N N, adapted as they are pressed backward or pulled forward to apply friction to the forward wheels or to relieve them therefrom.

P P are rearwardly-extending arms fixed on the tongue C, and consequently on the brake-bar M, and receiving the bolt G in slots p p, 55 which extend forward and backward, so as to allow a considerable forward and backward movement while being supported vertically by and free to tilt, if required, on the bolt G. The arms P P diverge rearward. They stand, 60 preferably, at an angle of about ten degrees, their rearward ends being connected and strongly braced by a rigid cross-piece, Q.

The parts are so formed and proportioned that when the force of the animals is applied 65 through the tongue C, or through any other suitable means, as thills, (not shown,) to hold back, it will disengage the arms P P from their tight embrace between the correspondingly-inclined hounds E E, and will move back 70 freely until the brakes N N are in contact with the wheels. Any forward pressure exerted by the wagon in descending a hill will result in increasing the friction. On the animals resuming their forward pull the brake-bar and 75 its attachments move forward freely; but so soon as they have effectually removed the brakes from the wheels the inclined outer faces of the arms P P begin to wedge tightly within the correspondingly-formed faces of 80 the hounds. When the pull becomes strong, the parts are very firmly set, and the wheels and the tongue remain as stiffly and efficiently connected as may be desired.

The divergence of the arms P P and corresponding position of the adjacent surfaces serve an end additional to the steadyng of the tongue when pulled forward in preventing the brakes from being allowed to come in contact with the wheels when the pulling force of 90 the animal or animals is simply relaxed. The considerable friction due to the tight embrace as the tongue is drawn forward holds it well forward and entirely frees the wheels from the brakes until the crowding of the wagon 95 forward in descending a hill becomes quite strong. I consider this a decided advantage in the miscellaneous work of a farm.

Previous to backing, the attendant pulls up on the chain I, attached loosely to the forward 100 end of the body A. This lifts strongly on the lever J, hinged to the under side of the tongue at the point j. On the rear arm of this lever is a stout block, J'. This may be of wood or

other cheap material, and may be only roughly shaped. It should be of such size as to nearly fill the space which exists between the cross-piece Q and the bolster B when the team has 5 pulled the movable parts forward. Taking care to pull this chain, and thus lift the block J' into position prior to backing, and to hold the chain up by the continued effort of the hand, or by attaching it to something, the 10 driver proceeds to back the team in the ordinary way. The arms P slide backward but little—not sufficient to quite release their close embrace between the hounds E E, when the presence of the block J' asserts itself to prevent any further backward movement, and the 15 brakes are not applied, but the force of the animals is applied in backing in the ordinary manner.

I am aware that there have been many efforts to apply self-acting brakes to farm vehicles. The demand therefor in hilly districts is very strong; but, so far as I am aware, all have been subject to the objection that they were complicated and costly, or that they did 25 not efficiently provide for the several conditions additional to braking: that they shall

maintain a stiff connection between the tongue and the axle under ordinary conditions of work; that they shall leave the tongue free to rock, as mine does, on the bolt G, and that they 30 are by the exercise of sufficient strength from the driver's seat made instantly ready for backing.

I claim as my invention—

In an automatic brake for wagons, the lever 35 J, hinged to the tongue at j, and carrying the block J', in combination with the operating cord or chain I, and with the wheels H H, axle D, hounds E E, cross-bolt G, divergent arms P P, having the slots p, brace Q, tongue 40 C, or equivalent means of attaching to the team, brake-bar M, and brakes N, arranged to serve as herein specified.

In testimony whereof I have herein set my hand, at Roslyn, New York, this 14th day 45 of February, 1887, in the presence of two subscribing witnesses.

SILAS W. ALBERTSON.
